UNITED STATES PATENT OFFICE.

CHARLES A. LIND, OF SAN JOSE, CALIFORNIA, ASSIGNOR OF ONE-FOURTH TO CHARLES B. LEWTON, OF SAN JOSE, CALIFORNIA.

AEROPLANE.

1,304,187.

Specification of Letters Patent. Patented May 20, 1919.

Application filed August 16, 1918. Serial No. 250,181.

To all whom it may concern:

Be it known that I, CHARLES A. LIND, a citizen of the United States, and resident of San Jose, in the county of Santa Clara and State of California, have invented certain new and useful Improvements in Aeroplanes, of which the following is a specification.

My invention relates to aeroplanes and particularly to a direct lifting and stabilizing device for the same.

One object of my invention is to provide a means whereby an aeroplane may be raised in a substantially vertical direction directly from the ground, thereby obviating the necessity of providing a runway for the same. Another object of my invention is to provide a means of the character indicated that may also be adapted for use as a stabilizing device or to assist in the forward movement of the air craft.

With these and other objects in view my invention consists in the novel and useful provision, formation, construction, combination and relative arrangement of parts, members and features, all as hereinafter described, shown in the drawings, and finally pointed out in the claims.

In the drawings:—

30 Figure 1 is a perspective view of one propeller.

Fig. 2 is a transverse sectional view of a propeller in position in its case and provided with a shutter.

35 Fig. 3 is a perspective view of an aeroplane equipped with my invention with stabilizing unit positioned in the fore part of the machine.

Fig. 4 is a diagrammatical plan view of 40 the arrangement of the several units and operating mechanism as applied to the aeroplane shown in Fig. 3.

Fig. 5 is a side elevation of an aeroplane equipped with my invention with stabilizing unit positioned in the rear of the machine.

Fig. 6 is a diagrammatical plan view of 50 the arrangement of the several units and operating mechanism as applied to the aeroplane shown in Fig. 5.

Fig. 7 is a side elevation of an aeroplane of large size for carrying freight and passengers and equipped with my invention.

Fig. 8 is a diagrammatical plan view of 55 the arrangement of the several units and

operating mechanism as applied to the aeroplane shown in Fig. 7.

Fig. 9 is a diagrammatical illustration showing method of operating the shutter of my device.

Fig. 10 is a diagram illustrating the method of operating the shutter when the device is used both for forward driving and as a stabilizer.

Fig. 11 is a perspective view of a propeller casing with the shutter attached and equipped with air diffusion vanes.

Similar characters of reference indicate similar parts throughout the several views.

Referring now more particularly to the drawings, 1 indicates the fuselage of an aeroplane provided with gliding planes 26 and the usual propeller 1^a and having recesses 2 formed in its opposite sides. In each recess 2 is positioned a propeller casing 3, the same being secured rigidly in position and provided with air exhaust perforations 4. In casing 3 is mounted a rotating shaft 5 which in turn carries propeller blades 6 and is operated by any suitable driving power as a motor 7 in casing 8. Any desired number of propeller blades 6 may be used, each blade being positioned longitudinally of the shaft and preferably curving in the direction of rotation of said shaft, and the shaft itself preferably rotating in a plane parallel with the axis of the fuselage of the air craft, or the gliding plane thereof. Blades 6 are also oblong in shape and of suitable length for the object in view.

Motor 7 is driven by dynamo 9 through the medium of wires 10 and 12 in which is operatively connected a controlling switch 11 and such other devices as may be necessary. In Figs. 3 and 4 the propellers are 95 arranged in pairs on each side of the aeroplane and a third pair positioned transversely of the plane and forward of the gliding planes as at 13. In operation when switch 11 is closed the various propellers are 100 rotated at high speed in the direction indicated by the arrows, the reaction of the air against their under surfaces forcing the whole machine to rise in a substantially vertical direction. This action will be facilitated by the propellers because their constant rotation at high speed will tend to remove the air from the top of the machine

105 and force it under the same, thereby rarefying the air above the machine and com- 110

pressing it below. While in the air the usual driving propeller 1^a may be stopped and the propellers embodying my invention put into motion and the air craft caused to 5 soar or hover at will.

The casing 3 may be provided with a shutter 14 pivoted thereon as at 15, in Fig. 11, and fitted with a shifting mechanism as rod 16 and lever 17, so that the said shutter 10 may be withdrawn into an inoperative position as shown in solid lines in Figs. 2-9 and 11 or thrown forward to further inclose propeller blades 6 as indicated by the arrow 18. The lever 17 by which rod 16 is operated 15 is preferably located in the fuselage of the aeroplane at a point adjacent controlling switch 11 as indicated in a formal manner in Fig. 8. Casing 3 may also be provided with diffusion vanes 19 so that when 20 a blade 6 enters casing 3 a definite path of travel will be provided for a portion of the air contained therein, the same being directed outwardly to the exhaust perforations 4 thereby preventing the formation of 25 pockets in the said casing 3. The lower half of casing 3 is extended downwardly so that diffusion vanes 19 may be inserted therein without interfering with the rotation of blades 6, as shown in Fig. 2.

30 When in the position 13 in Figs. 3 and 4 the blades 6 may also be used to assist in driving the air craft forward after the same has been raised a sufficient distance to secure a clear path of travel by constructing the 35 casing 3 as shown in the diagram in Fig. 10. That is, with but a quarter-section of its end closed so that the rod 16 and lever 17 may be used to throw the shutter 14 into the position 19 so that the device may be 40 used as a direct lift or stabilizing device or to throw the shutter 14 into the position 20 so that the device may be used to assist in driving the machine forward. It is obvious of course that the shutter may be easily 45 adapted for forward movement from above or below as desired.

In Figs. 5 and 6 I have shown the invention applied to a small aeroplane in which the tail 21 is weighted slightly and fitted 50 with a transversely positioned stabilizer at 22, a pair of the devices being positioned on each side of the machine as at 23 and 24 and 23^a and 24^a respectively. The propellers in this instance are operated in substantially 55 the same manner as described in connection with Figs. 3 and 4 except that transverse propellers 22 are operated upon a separate electrical circuit indicated by wires 12^a and controlled by a switch 12^b so 60 that they may be operated entirely independently of the side propellers.

Figs. 7 and 8 illustrate a contemplated application of my invention showing how they may be used when applied to large air 65 ships for passenger, mail or freight service.

In this embodiment 25 indicates the body of the machine provided with gliding planes 26 and pilot's house 27. Three pairs of propellers are here shown on each side of the air craft as at 28-29-30 and 28^a-29^a and 70 30^a respectively, and two more pairs positioned in the front and rear as at 31 and 32 respectively. The side elements are here placed well above the center of gravity of the air-ship in order to secure better balance. The roof of the air-ship, 25^a, slopes 75 to the sides to facilitate the removal of the air from above the same. These various pairs of propellers may be operated by individual motors connected to a central power unit 33 by wires 10 and 12 provided with switch 11. The shutters of all of the pairs on one side may be operated by a lever 17 and rod 16 operating shaft 34 to which each shutter is connected by a rod as indicated 80 at 35, the mechanism for the four groups of shutters being designated by similar numerals followed by an appropriate letter.

It is understood of course, that the propeller blades may be made in any suitable 90 form, assembled in any suitable combinations and operated in any suitable manner in connection with any desired accessories and in conjunction with the various operating mechanisms of the air-craft, as 95 with the ordinary propeller and with the various types of gliding planes. Also speed regulating devices may be inserted in the power transmitting lines as at 12^c in Fig 4. The forms and applications of the invention 100 herein shown and described are for the purpose of illustration only and therefore are not to be understood to in any way limit the scope of my invention which is intended to include all that may be included within the 105 scope of the appended claims.

I claim:

1. In an aeroplane, a propeller comprising a shaft operatively mounted on the body thereof substantially parallel with the gliding plane thereof, a plurality of oblong blades projecting outwardly from the perimeter of said shaft and operating means for said shaft, and a casing having perforated ends inclosing a portion of said propeller. 110

2. In an aeroplane, a propeller comprising a shaft operatively mounted on the body thereof substantially parallel with the gliding plane thereof, a plurality of oblong blades projecting outwardly from the perimeter of said shaft and operating means for said shaft, and a casing having air diffusion vanes positioned therein inclosing a portion of said propeller. 120

3. In an aeroplane, a propeller comprising a shaft operatively mounted on the body thereof substantially parallel with the gliding plane thereof, a plurality of oblong blades projecting outwardly from the perimeter of said shaft and operating means for 125 130

said shaft, and a casing having air diffusion vanes starting from its lower edge substantially midway of its length and terminating at the rear of each end inclosing a portion 5 of said propeller.

4. In an aeroplane, a propeller comprising a shaft operatively mounted on the body thereof substantially parallel with the gliding plane thereof, a plurality of oblong 10 blades projecting outwardly from the perimeter of said shaft and operating means for said shaft, and a casing having perforated ends and provided with air diffusion vanes inclosing a portion of said propeller.

15 5. In an aeroplane, a propeller compris-

ing a shaft operatively mounted on the body thereof substantially parallel with the gliding plane thereof, a plurality of oblong blades projecting outwardly from the perimeter of said shaft and operating means for 20 said shaft, and a casing having perforated ends and having air diffusion vanes starting from its lower edge substantially midway of its length and terminating at the rear of said perforated ends inclosing a portion of 25 said propeller.

In testimony whereof I have hereunto affixed my signature this 10th day of August, 1918.

CHARLES A. LIND.
